UNITED STATES PATENT OFFICE.

JOHN DINGIROGLOU, OF PORTLAND, OREGON.

OIL BURNER.

Application filed December 1, 1921. Serial No. 519,226.

To all whom it may concern:

Be it known that I, JOHN DINGIROGLOU, a citizen of the United States, residing at Portland, in the county of Multnomah and State of Oregon, have invented a new and useful Oil Burner, of which the following is a specification.

The device forming the subject matter of this application is a burner, adapted to be used in connection with fluid fuel. The invention aims to provide novel means for controlling the flow of the fuel, and to provide novel means for cleaning the device.

It is within the province of the disclosure 15 to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in 25 the precise embodiment of the invention shown can be made without departing from the spirit of the invention.

In the accompanying drawings:—

Figure 1 shows in longitudinal section, a 30 device constructed in accordance with the invention, parts being broken away, and parts appearing in section; Figure 2 is a side elevation of the hand wheel and attendant parts; Figure 3 is a transverse section on the line 3—3 of Figure 1; Figure 35 4 is a transverse section on the line 4—4 of Figure 1. Figure 5 is a cross section taken through the hub of the hand wheel and parts therewithin.

The device forming the subject matter of 40 this application includes a body comprising a tubular member 60. A cup-shaped nozzle 61 is provided, the same being threaded at 62 on the forward end of the tubular member 60, the nozzle including an end wall 63 having an outwardly extended seat 64 wherein an outlet 65 is fashioned. A tubular guide 66 is located within the nozzle 61 and is provided at its forward end with 45 an outstanding flange 67 abutting against the end wall 63 of the nozzle. At its rear end, the tubular guide 66 is supplied with radial arms 68 extended within the forward end of the tubular member 60, and having 50 fingers 69 engaging the forward end edge of the member 60. Obviously when the nozzle

61 is threaded on the tubular member 60, the guide 66 will be held in the position shown in Figure 1. In the flange 67 and in the guide proper 66, slits or ports 70 are formed, the same being disposed tangentially to the bore of the guide 66, the inner ends of the slits 70 communicating with the interior of the guide 66, and the outer ends of the slits communicating with the chamber which exists in the nozzle 61, about the guide 66.

The numeral 71 denotes a foot the rear end of the tubular member 60 being threaded into the foot or being mounted otherwise there-in. The foot 71 has a lateral inlet 72.

A plunger, denoted generally by the numeral 73, is mounted to slide in the body of the burner, the plunger being a composite structure and including a tube or guide 74. 75 A valve 75 is mounted removably in the forward end of the tube 75 and is slidably received in the tubular guide 66, the forward end of the valve being so shaped that it will cooperate with the outwardly extended seat 64 in the end wall 63 of the nozzle 61, and control the passage of fuel through the outlet 65. The plunger 73 embodies a screw 76, wherein the rear end of the tube or guide 74 is mounted. The screw 76 is threaded at 79 into the foot 71 and has an external shoulder 90, the screw 76 having a reduced neck 77 including a polygonal part 110. The neck 77 has an internal shoulder 78. The numeral 79 marks a hand wheel comprising a tubular hub 80 provided at its inner end with a flange 81, the flange having a polygonal open 111 receiving the part 110 of the neck 77 of the screw 76 and abutting against the shoulder 78. A nut 82 is threaded on the rear end of the neck 77 of the screw 76 and is located within the hub 80 of the hand wheel 79, the nut bearing against the flange 81, and binding the same against the shoulder 78 the construction being such that when rotation is imparted to the hand wheel 79, rotation will be imparted to the screw 76 and to the other parts of the plunger 73 hereinbefore alluded to.

On its outer surface, the hub 80 of the hand wheel 79 is provided with a scale 83, constructed as desired. A carrier 84, in the form of a collar is circumferentially adjustable on the rear end of the foot 71, and is held in place, adjustably, by a set screw 85, threaded into the carrier and adapted to cooperate with a circumferential seat 86

fashioned in the rear end of the foot 71. The carrier 84 embodies a rearwardly extended arm 87, the rear end of which is disposed close to the hub 80 of the hand wheel 79, the arm carrying a vernier 88 adapted to coact with the scale 83 on the hub 80 of the hand wheel 79.

5 A stop ring 91 is located in the rear end of the foot 71 and abuts against an internal shoulder 92, formed in the foot 71. A packing 93 surrounds the neck 77 of the screw 76 and abuts against the stop ring 91. An annular pressure member 94 is received slidably within the rear end of the foot 71, the neck 77 of the screw 76 sliding in the pressure member, in the packing 93 and in the stop ring 91. A nut 95 is threaded externally on the rear end of the foot 71, the nut and the pressure member 94 being supplied 10 with cooperating annular flanges 96, the construction being such that when the nut 95 is advanced, the pressure member 94 will be advanced likewise, the packing 93 being compressed about the neck 77 of the screw 76.

15 In practical operation, rotation may be imparted to the plunger 73, by means of the hand wheel 79 and because the screw 76 is threaded at 89 into the foot 71, the plunger 73 may be retracted from the position shown 20 in Figure 1, the forward end of the valve 75 being spaced from the end wall 63 of the nozzle 61. Under such circumstances, the fuel will enter through the inlet 72 and will traverse the tubular member 60, the fuel passing between the arms 68 of the guide 66, and entering the chamber which exists about the guide and within the nozzle 71. Proceeding from thence, the fuel traverses the slits or ports 70 in the flange 67, 25 and enters the tubular guide 66 in advance of the retracted valve 75, the fuel deriving a whirling motion, and issuing in a flame from the outlet 65.

30 It is obvious that the plunger 73 may be adjusted forwardly or backwardly, to a fine degree, owing to the fact that the arm 87 is provided with the vernier 88 coacting with the scale 83 on the hub 80 of the hand wheel. It is possible to loosen the set screw 85, 35 whereupon the carrier 84 and its arm 87 may be shifted circumferentially of the part 7, to the end that the vernier 88 may be so set as to be read without difficulty, due regard being had to the way in which the device is 40 mounted in a boiler furnace. Referring to Figure 5, it will be seen that the hand wheel 79 may be adjusted circumferentially on the part 110, the construction and operation being such that the zero of the scale 83 may be 45 at the top and exposed plainly to view, regardless of the position of the outlet 72.

As thus far described, the device embodies means whereby the flow of fuel may be regulated to a fine degree. It is contemplated, 50 further, that means shall be provided where-

by, at the will of an operator the outlet 65 may be cleaned. With this end in view, the device includes a cleaner, denoted generally by the numeral 97, and mounted for reciprocation in the plunger 73. The cleaner 97 includes a main member 98 in the form of a rod, mounted to reciprocate in the tube 74, the tube acting as a guide for the rod. The rod or main member 98 is slidably, further in the screw 76 and in the neck 77 thereof. A tip 99, in the form of a pin, is secured removably at 100 to the forward end of the rod 98 and is mounted for reciprocation in the valve 75. A recess 101 is formed in the neck 77 of the screw 76 and therein a compression spring 102 is located. The forward end of the compression spring 102 abuts against the neck 77 of the screw 76, the rear end of the compression spring engaging an abutment 103, attached by a securing element 104 to the main member or rod 98 and received slidably in the recess 101 of the neck 77. A packing 105 surrounds the rod 98 and is located in a cavity in the nut 82. A screw plug 106 is threaded into the nut 82 and serves as a means for compressing the packing 105 about the rod 98, the rod being mounted slidably in the screw plug. A finger piece 107 is secured at 108 to the outer end of the rod 98 and is adapted to be received in a chamber 109, formed in the hand wheel 79.

It will be obvious that reciprocation may be imparted to the cleaner 97, through the instrumentality of the finger piece 107, the spring 102 being compressed when the cleaner is advanced, and serving to assist in the rearward movement of the cleaner. When the cleaner is reciprocated, the tip 99 of the cleaner moves in and out of the outlet 65, accumulations of carbon or other foreign material being removed from the outlet 65. When the cleaner 97 is retracted, due to the action of the spring 102, the abutment 103 engages the nut 82, the forward end surface of the tip 99 being located flush with the forward end surface of the valve 75, it thus being impossible for carbon to accumulate in the bore of the valve 75 wherein the tip 99 operates.

What is claimed is:—

1. In a device of the class described, a body having an outlet; a plunger threaded into the body for longitudinal movement and controlling the outlet; a carrier shiftable on the body circumferentially thereof; and means for holding the carrier in adjusted position circumferentially of the body, a portion of the carrier, and the plunger, being provided with coacting graduations.

2. In a device of the class described, a body comprising a tubular member; a nozzle on the tubular member and having an outlet; a tubular guide held by the nozzle

on the tubular member and supplied with a flange cooperating with the forward end of the nozzle, the flange having a radial slit communicating with the bore of the guide; 5 and a plunger comprising a valve mounted slidably in the guide.

3. In a device of the class described, a tubular body, a nozzle on one end of the body, a plunger threaded into the body and co- 10 operating with the nozzle, the plunger comprising a member having an internal recess and an external shoulder, a hand wheel including a part surrounding said member and abutting against the shoulder, a cleaner for 15 the nozzle and slidable in the plunger, a compression spring in the recess and surrounding the cleaner, an abutment on the cleaner and coacting with the spring, and a retainer on said member of the plunger, the 20 retainer constituting a stop for the abutment, and serving to hold said part of the hand wheel against the shoulder.

4. In a device of the class described, a tubular body, a nozzle on the body, a plunger 25 threaded into the body and cooperating with the nozzle, the plunger comprising a member having an internal recess and an external shoulder, a hand wheel including a hollow hub surrounding said member and abut- 30 ting against the shoulder, a cleaner for the nozzle and slidable in the plunger, a com-

pression spring in the recess, an abutment on the cleaner and coacting with the spring, the abutment being slidable in the recess, a retainer on said member of the plunger 35 within the hub of the hand wheel, the retainer constituting a stop for the abutment and coacting with the hub of the hand wheel to hold the same in cooperating relation to the shoulder, and means carried by the retainer for guiding the cleaner, the cleaner being slidable in the retainer.

5. In a device of the class described, a tubular body, a nozzle on the body, a plunger threaded into the body and controlling the 40 nozzle, a packing device on the body and coacting with the plunger, a collar circumferentially adjustable on the body and provided with a rearwardly extended arm so constructed as to permit the mounting of the 45 packing device on the body, means for holding the collar in adjusted positions circumferentially of the body, and means for rotating the plunger, said means and the arm having cooperating graduations. 50

In testimony that I claim the foregoing as my own, I have hereto affixed my signature in the presence of two witnesses.
